DANIEL S. COLBY AND ROBERT SCORER, OF TROY, NEW YORK, ASSIGNORS TO EDWARD J. HICKS AND GURDON G. WOLFE, OF SAME PLACE.

Design No. 2,963, dated March 31, 1868.

DESIGN FOR A STOVE-DOOR.

The Schedule referred to in these Letters Patent and making part of the same.

TO ALL WHOM IT MAY CONCERN:

Be it known that we, DANIEL S. COLBY and ROBERT SCORER, each of the city of Troy, in the county of Rensselaer, and State of New York, have jointly invented or produced a new and original Design for Stove-doors, of which the following is a full and exact description, reference being had to the accompanying photograph of a stove-door having our said design.

The distinguishing feature of this design is the arrangement of the compound ornament A, on the middle portion, and mouldings B along the border of the surface C of a stove-door, so as to present an appearance like that represented by the aforesaid photograph.

What we claim as our invention or production, and desire to secure by Letters Patent, is—
The design for stove-doors herein set forth and shown.

In testimony whereof, we have hereunto set our hands, this 11th day of February, 1868.

DAN'L S. COLBY,
ROBERT SCORER.
